United States Patent Office.

LEO DAFT, OF NEW YORK, N. Y., ASSIGNOR TO ~~MYSELF AND~~ JOHN WOOD, OF SAME PLACE.

Letters Patent No. 87,644, dated March 9, 1869: antedated November 20, 1868.

IMPROVED ELASTIC SEAT AND BACK FOR CHAIRS AND BOTTOM FOR BEDS

The Schedule referred to in these Letters Patent and making part of the same.

To all whom it may concern:

Be it known that I, LEO DAFT, (British subject,) of New York, in the county and State of New York, have invented a new and useful Improvement in Elastic Seats, Backs, and Bed-Bottoms; and I do hereby declare that the following is a full, clear, and exact description thereof, which will enable others skilled in the art to make and use the same, reference being had to the accompanying drawings, forming part of this specification.

This drawing represents a perspective view of a chair provided with my improved elastic seat and back.

This invention relates to a new manner of forming or constructing the backs and seats of chairs, or other surfaces, where springs or cushions are usually employed, and consists in forming such seats, backs, or surfaces of cords, bands, tubes, or narrow strips, of India rubber, such tubes, bands, cords, or strips, being either interwoven, in imitation of cane chair-seats, or of wire netting, or in any other suitable manner, or they are arranged parallel to each other, or in any suitable fanciful design.

A very convenient seat, back, or couch will, by this arrangement, be produced, in a simple and inexpensive manner.

A, in the drawing, represents the frame of a chair.

The seat, as well as the back of the same, is represented as being formed of narrow strips, *a a*, of India rubber, either interwoven in suitable manner, as on the seat, or arranged parallel to each other, as on the back, or otherwise arranged, so as to form an elastic surface.

The India rubber used may be prepared in the ordinary or in any suitable manner.

I claim as new, and desire to secure by Letters Patent—

Elastic seats, backs, and bed-bottoms, made of India-rubber strips, interwoven and arranged substantially as herein shown and described.

LEO DAFT.
